UNITED STATES PATENT OFFICE.

JOHN W. POST, OF NEW YORK, N. Y.

OPERATING DEVICE FOR THE WINDOWS OF RAILWAY-CARS.

SPECIFICATION forming part of Letters Patent No. 369,298, dated August 30, 1887.

Application filed November 24, 1886. Serial No. 219,708. (No model.)

To all whom it may concern:

Be it known that I, JOHN W. POST, a citizen of the United States, residing at the city of New York, in the county of New York and State of New York, have invented certain new and useful Improvements in Operating Devices for the Windows of Railway-Cars; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to devices to be employed for the purpose of closing and locking the windows of railway-cars. On lines of railways passing through tunnels it becomes necessary to close and keep closed until the tunnel is passed all the windows of a car, to prevent the ingress of smoke and cinders. In order to do this with the cars now in general use it is common for a brakeman or other employé to pass through each car, close the open windows, and inform the passengers that the train is approaching a tunnel, and that the windows should not be opened until it is passed; but even with this notification many persons, regardless of the comfort of the other passengers, will reopen the window. It therefore becomes advisable under such circumstances to not only close the windows, but to have means provided for locking them in that position, so that it will be impossible for the passengers to open them until in the opinion of the conductor or other person in charge of the car it is advisable to do so. Again, it sometimes happens that selfish persons will insist upon keeping a window open utterly regardless of the health or comfort of the passengers occupying the seats behind them and who receive the full force of the blast entering the open window, together with its usual accompaniment of cinders, directly in their faces, to the great danger of injury to their eyes and lungs, while the evil-doer is enjoying a gentle breeze. It therefore becomes desirable to provide means by which the suffering parties may close the offending window without the permission of the party who occupies the adjacent seat.

The object of this invention is, therefore, first, to provide means by which all the windows may be closed and locked from either end of the car; secondly, to afford the passengers facilities for closing open windows at a distance therefrom when they find themselves incommoded by their being purposely kept open, either by vicious or careless passengers; and these objects I accomplish by providing each window with a movable side casing connected with a longitudinal shaft extending nearly the whole length of the car, and a similar shaft for operating the window-locking devices, all constructed and arranged in the manner hereinafter described.

In the accompanying drawings, Figure 1 is an interior view of one side of a car provided with my improved window-operating devices. Fig. 2 is a vertical section on line 1 1 of Fig. 1. Fig. 3 is a similar section on line 2 2 of Fig. 1, and Fig. 4 shows a part of a side of the car with its interior covering removed to illustrate the operation of the window closing and locking devices.

In constructing a car provided with my improved window closing and locking appliances, the side of the car A is allowed to project inward, as at A', to form a covering or casing for the shafts B and C, which extend horizontally nearly the whole length of the car over the windows. These shafts each have a sliding endwise movement in the brackets a and b, by which they are carried. The shaft B is provided with a series of collars, a' a', placed nearly in line with the side casing of each window. This casing D on that side of the window adjacent to the collars on the shaft B is made movable, being pivoted at b', so that when its upper end is moved in one direction by the collars upon shaft B its lower end moves in the opposite direction.

In order to allow the casing to be acted upon by the collars a', its upper end above the pivot b' is bent inward toward the middle of the car, so as to bring its upper end in line with shaft B, and this upper end is either bifurcated or has a hole formed through it of sufficient size to allow the shaft to pass easily.

A series of holes, c c, are formed in the casing D for the reception of the bolt c' of the window-lock E, which bolt, when the piece D is in its normal position, enters either of the

holes *c*, as may be desired, the functions of this part of the casing when in its normal position being the same as in the ordinary casing; but when it is desired to close the windows on either side of the car, one or more of them being open, the brakeman or other person takes hold of the hand-lever *F*, and by a movement in the proper direction gives to the shaft *B* (with which the upper end of the lever is connected) an endwise movement, by which means the collars *a* upon the shaft are brought in contact with the upper end of each of the side pieces, *D*, oscillating them upon their pivots and causing their lower end to swing 15 away from the window, thus releasing the bolt *c*, so that all open windows at once fall into the closed position. When the hand-lever is released, the spiral spring *d*', bearing against the pieces *D*, returns them to their proper position.

When it is desired to close but one window, it may be done by means of the lever *G*, pivoted at the rear side of the window it is intended to act upon. These levers *G* are connected at their upper ends with a rock-shaft, *e*, carrying an arm, *e*', the ends of which rest in contact with the piece *D*, above its pivot. From this construction it is apparent that if the lower end of the lever *G* is swung to the rear, the arm *e*', bearing against the upper part of the piece *D*, will force it over, causing its lower end to release the bolt of the adjacent window and allow the latter to close. By placing one of these devices between each pair 35 of windows it will be seen that the party occupying the seat in rear of another may close the window of the seat in front of him without difficulty.

In order to lock all the windows on one side 40 of a car simultaneously, each window-frame is provided with a notch, *n*, to receive the projecting toe of a stop-lever, *H*, pivoted at *i* to the side of the car and having its upper end connected with the shaft *C*. This shaft is connected to a hand-lever, *I*, pivoted to the side 45 of the car, and, like the lever *F*, extending downward into a suitable position to be readily grasped by an operator, who, by moving the lever, gives to the shaft *C* an endwise movement, causing the collars *a*' thereon to bear 50 against the upper end of the stop-levers and force the toes upon their lower ends into the notches *n* of the window-frames, thus locking them securely in a closed position.

55 Spring *d*'' may be placed behind the stop-levers to hold them out of engagement with the window-frames, except when it is desired to securely lock them in a closed position, as in passing through a tunnel; and any suitable 60 locking devices may be applied to the hand-levers *F* and *I* to retain them in the desired position and prevent them from being operated accidentally or purposely by the passengers.

65 I am aware that sash-fastening devices have been invented in which the sash was retained in any desired position by swinging spring-

operated stop-levers, and that a movable notched side bar placed at one side of the sash and adapted to receive a supporting-pin 70 attached to said sash for the purpose of entering one of the notches of said side bar has been used. I do not, therefore, broadly claim such stops or notched side bars, but limit my claims to the perforated side bars placed in 75 line with the sash and receiving in its perforations a movable catch-pin attached to said sash and the mechanism for operating these supporting and locking devices in a railway passenger-car.

Having thus described my invention, I claim as new, and desire to secure by Letters Patent, the following:

1. In a passenger-car, the pivoted and perforated longitudinally-swinging side piece, in 85 combination with the window and its movable locking-bolt arranged to enter one of the series of holes in the pivoted side pieces and lock the window, substantially as described.

2. In a passenger-car, the combination of 90 the windows and their locking-bolts, the longitudinally-swinging pivoted and perforated side pieces to the window-frames, engaging with said bolts, and the longitudinally-movable shaft *B*, having collars *a*' thereon, adapted 95 to move all the swinging side pieces upon one side of the car for the purpose of unlocking all the windows upon that side simultaneously, substantially as set forth.

3. In a passenger-car, the combination, with 100 the windows and their locking-bolts, of the longitudinally-swinging side pieces engaging with said locking-bolts, the spring *d*', acting upon said side pieces, the shaft *B*, provided with collars *a*', and the pivoted hand-lever *F*, 105 arranged to operate said shaft and swing the side pieces for the purpose of unlocking all the windows upon one side of the car simultaneously, substantially as set forth.

4. In a passenger-car, the combination of a 110 window and its locking-bolt with a swinging and perforated side piece, *D*, its perforations engaging with said bolt, a hand-lever, *G*, and rock-shaft *e*, having an arm, *e*', projecting from said rock-shaft, adapted to bear upon 115 and swing said side piece to unlock a single window of the car independently of the other, as set forth.

5. In a passenger-car, the combination, with 120 a window having a notch, as *n*, in its sash, of a pivoted spring-pressed swinging stop provided at its lower end with a toe or projection for entering said notch, and a longitudinally-moving shaft, *C*, provided with a collar, as *o*, to act upon said swinging stop when the 125 shaft is moved in one direction and lock the window, substantially as set forth.

6. In a passenger-car, the hand-lever *I*, longitudinally-moving shaft *C*, provided with collars *o*, pivoted swinging stops *H*, and spring 130 *d*'', bearing against said stops, in combination with the window-sashes upon one side of the car, said sashes having notches *n*, to receive the toe of the said swinging stops and afford a

means of locking said windows simultaneously, substantially as shown and described.

7. In a passenger-car, the perforated swinging side pieces and swinging stop-levers pivoted between the inner and outer sides of the car and the longitudinally-moving shafts for operating said side pieces and stop-levers, in combination with a window-sash having a spring-bolt upon one side to enter the perforations of the side pieces and a notch upon the

other to receive the toe of the stop-lever, all arranged, as shown and described, to lock and unlock the windows upon one side of the car simultaneously.

In testimony whereof I affix my signature in presence of two witnesses.

JOHN W. POST.
